UNITED STATES PATENT OFFICE.

JOHN F. REEDER, OF SHELBYVILLE, ILLINOIS.

DESIGN FOR A SHOE-CLASP.

45,432.

Specification for Design.

Patented Mar. 17, 1914.

Application filed January 17, 1914. Serial No. 812,853. Term of patent 7 years.

To all whom it may concern:

Be it known that I, JOHN F. REEDER, a citizen of the United States of America, residing at Shelbyville, in the county of Shelby and State of Illinois, have invented a new, original, and ornamental Design for Shoe-Clasps, of which the following is a specification, reference being had to the accompanying drawing, forming part thereof.

The figure is a perspective view of a shoe clasp showing my new design.

I claim:

The ornamental design for a shoe clasp as shown.

JOHN F. REEDER.

Witnesses:

W. E. LOWE,

A. B. WADE.
